UNITED STATES PATENT OFFICE

SIDNEY O. BRIGGS, OF SUFFOLK, VIRGINIA

DESIGN FOR A BOTTLE.

Application filed May 9, 1929. Serial No. 31,151. Term of patent 14 years.

To all whom it may concern:

Be it known that I, SIDNEY O. BRIGGS, a citizen of the United States of America, and resident of the city of Suffolk, county of Nansemond, and State of Virginia, have invented a new, original, and ornamental Design for a Bottle, of which the following is a specification, reference being had to the accompanying drawing, forming part thereof.

I claim:

The ornamental design for a bottle as shown.

SIDNEY O. BRIGGS.
